US00D540945S

(12) **United States Design Patent** (10) **Patent No.:** **US D540,945 S**
Darnold et al. (45) **Date of Patent:** **** Apr. 17, 2007**

(54) **PERIODONTAL SCALING TIP FOR
ULTRASONIC DENTAL HANDPIECE**

(75) Inventors: **Leane Darnold**, Kirkwood, MO (US);
Doxey Phillips, Huntleigh, MO (US)

(73) Assignee: **Young OS, LC**, Fenton, MO (US)

(**) Term: **14 Years**

(21) Appl. No.: **29/199,700**

(22) Filed: **Feb. 18, 2004**

(51) **LOC (8) Cl.** **24-02**

(52) **U.S. Cl.** **D24/152; D24/133; D24/146;**
D24/147; D24/156

(58) **Field of Classification Search** **D24/111,**
D24/146, 156, 176, 217, 147, 144, 112; 451/165,
451/28, 910; 433/119, 165, 125, 29, 215,
433/141, 86

(57) **CLAIM**

The ornamental design for a periodontal scaling tip for ultrasonic dental handpiece, as shown and described.

DESCRIPTION

FIG. 1 is a perspective view of a periodontal scaling tip for ultrasonic dental handpiece showing our new design;

FIG. 2 is a top plan view thereof;

FIG. 3 is a bottom plan view thereof;

FIG. 4 is a right elevational view thereof;

FIG. 5 is a left elevational view thereof;

FIG. 6 is a front elevational view thereof;

FIG. 7 is a rear elevational view thereof;

FIG. 8 is a perspective view of the second embodiment design of a periodontal scaling tip for ultrasonic dental handpiece showing our new design;

FIG. 9 is a bottom plan view thereof;

FIG. 10 is a top plan view thereof;

FIG. 11 is a right elevational view thereof;

FIG. 12 is a left elevational view thereof;

FIG. 13 is a front elevational view thereof; and,

FIG. 14 is a rear elevational view thereof.

The broken line showing of the periodontal probe is included for the purpose of illustrating environmental structure and forms no part of the claimed design.
